UNITED STATES PATENT OFFICE.

GEORGE A. RAISBECK, OF BROOKLYN, ASSIGNOR TO THE PH. HAKE MANUFACTURING COMPANY, OF NEW YORK, N. Y.

DESIGN FOR WRITING-PAPER.

SPECIFICATION forming part of Design No. 20,911, dated July 7, 1891.

Application filed April 15, 1891. Serial No. 389,080. Term of patent 14 years.

To all whom it may concern:

Be it known that I, GEORGE A. RAISBECK, a citizen of the United States, residing in the city of Brooklyn, county of Kings, and State of New York, have invented and produced a new and original Design for Writing-Paper, of which the following is a specification, reference being had to the accompanying drawing, in which the figure thereon illustrates an open box of writing-paper in perspective, showing the upper sheet of the therein-contained package of paper.

The leading feature of my design consists of a peculiar figure decorated along its edges with small T-shaped figures.

A is a sheet of paper having thereon the

figure B, consisting of an upper neck-like portion *a*, beneath which extend the horizontal lines *b b*, that join to the curved upright line *d* and to the irregularly-curved upright line *e*, said lines *d* and *e* being joined by the curved bottom line *f*.

D D represent a line of T-shaped figures extending outwardly at slight intervals around the edge of the figure B, resembling tacks.

What I claim is—

The design for writing-paper, as herein shown and described.

GEORGE A. RAISBECK.
